UNITED STATES PATENT OFFICE.

LAWRENCE A. GRAY, OF MULLAN, IDAHO.

UNLOADER.

1,206,532.

Specification of Letters Patent. Patented Nov. 28, 1916.

Application filed March 8, 1916. Serial No. 32,732.

To all whom it may concern:

Be it known that I, LAWRENCE A. GRAY, a citizen of the United States, and a resident of Mullan, in the county of Shoshone and State of Idaho, have invented certain new and useful Improvements in Unloaders, of which the following is a specification.

The object of my invention is to provide an unloader connected with the intake of a multi-stage air or gas compressor, which automatically relieves the compressor of load when the pressure in the receiver or delivery line reaches a predetermined value and causes the compressor to take up full load again when the pressure falls below a critical point, and which obtains these results without loss of volumetric efficiency or power and without loss of compressed air trapped in the intercooler.

As distinguished from other unloaders of similar location, my invention is dependent neither upon a throttling of the intake, which causes overheating and loss of volumetric efficiency, nor upon the production of a vacuum in the compressor, which presents serious mechanical difficulties and also results in heating and loss of power if a practical vacuum be not obtained. My unloader closes the intake of the compressor without throttling when the receiver pressure arrives at the predetermined value, and thereupon places the intake in communication with the intercooler, so that thereafter the piston of the low pressure stage operates idly, taking air from and returning it to the intercooler, while the high pressure stage by its continued operation draws upon the partially compressed air stored in the intercooler until the pressure in the latter falls substantially to atmospheric conditions; then the intake of the low pressure stage is re-opened to the atmosphere, so that, during the succeeding period and until the receiver pressure falls below the critical value, atmospheric air is passed through the low pressure stage without having work done upon it, thereby relieving the compressor of a large part of its load and cooling the low pressure stage by the circulation of air therethrough. The high pressure stage now operates as a single stage compressor, receiving air at atmospheric pressure from the intercooler; it is to be understood, however, that additional means may be provided, if desired, for also unloading the high pressure stage. When

the pressure in the receiver or delivery line becomes less than the critical value, the communication between the intake of the low pressure stage and the intercooler inserted between the stages is closed, and, the intake remaining open to the atmosphere, normal load conditions are restored. A preferred embodiment of the unloader, comprising a combination of main valves, motors for operating the same and pilot valves and connections for controlling the operation of the motors so as to produce full opening and closing of the main valves in a predetermined order, dependent upon the conditions of receiver and intercooler pressures, will now be briefly described, but it is to be understood that numerous modifications are permissible and that the essential features of the invention may be embodied in other specifically different forms and combination.

In the accompanying drawings: Figure 1 is a vertical section through the unloader casing and valves, and through the casing containing the valve-operating pistons and pilot valves, the latter being shown partly in section and partly in elevation. This view shows the parts in the positions which they hold during the normal operation of the compressor. Fig. 2 is a vertical section on the line 2—2 of Fig. 1. Fig. 3 is a semi-diagrammatic plan view, showing how the unloader may be arranged with reference to the other parts of the compressor system. Fig. 4 is a horizontal section through the unloader casing and valves. Fig. 5 is an enlarged plan view of the upper casing and piping connections. Fig. 6 is a side elevation of the same. Fig. 7 is an enlarged elevation of pilot valve 47. Fig. 8 is an enlarged vertical section through pilot valve 48 in its chamber. Fig. 9 is an enlarged vertical section illustrative of another arrangement of springs for the main valves of unloaders of large size. Fig. 10 is a vertical section through the upper casing, the pistons and pilot valves within all being down. This is the condition which results when the receiver pressure has risen above the predetermined value, thereby forcing down the pilot valve 48, with the result that pistons 39 and 40 are forced downward in succession. Fig. 11 is a similar view, with piston 39 and pilot valve 47 up and pilot valve 48 and piston 40 still down. This is a condition succeeding that of Fig. 10, the inter-

cooler pressure having fallen sufficiently to permit valve 47 to rise, this valve then permitting air to exhaust from cylinder 41 so that piston 39 could also rise. Figs. 12 and 13 are elevations of one of the main valves and its reversible bushing.

Fig. 3 illustrates somewhat diagrammatically the relation of the unloader to a two-stage air compressor, of which 15 is the low pressure stage and 16 the high pressure stage. The unloader, designated as a whole by the numeral 17, is connected in the inlet pipe 18, as near as possible to the intake 19 of the low pressure stage. 20 is the outlet from the low pressure stage to the intercooler 21 and 22 is the pipe leading from the intercooler to the intake of the high pressure stage, from which the finally compressed air is delivered through pipe 23 to a receiver 24 connected with the high pressure line 25.

As illustrated, the unloader comprises a casing 26 having three connections, 27, 28 and 29, 27 being the inlet connection, 28 the outlet delivery to the intake of the low pressure stage, and 29 being connected with the intercooler through pipe 30. Interiorly the casing is divided by suitably arranged walls 31 to form three chambers open to the three connections, the chambers thus formed being an inlet or source chamber 32, an outlet chamber 33 communicating with the compressor intake, and a chamber 34 communicating with the intercooler. For convenience, therefore, these three chambers may be termed, respectively, the source chamber, the intake chamber, and the intercooler chamber. The top and bottom walls of the intake chamber 33 are formed with openings for two main double-seat valves 35, 36, the coöperating seats being designated 37 and 38. During normal operation the valve 35 remains open and the valve 36 closed. These valves are operated by suitable motors, comprising pistons 39 and 40 operating in fluid pressure cylinders 41, 42 against the action of compression springs 43, 44 surrounding the valve rods 45 and 46, on the upper ends of which the pistons 39 and 40 are loosely mounted. Under normal conditions these springs hold the pistons and the valves 35 and 36 in their highest positions, in which positions the valve 35 is open and the valve 36 is closed. When fluid pressure is admitted to the cylinders 41 and 42, above the pistons, the latter are driven downward, thereby seating valve 35 and opening valve 36, provisions being made, however, as presently described, whereby the second valve is not opened until after the first has been closed.

The operation of the fluid pressure pistons 39 and 40 is controlled by two pilot valves 47 and 48, in the nature of pistons, operating in cylindrical chambers 49 and 50.

The top of the chamber 50 is in communication with the receiver 24 through a small pipe 51, and the chamber 49 is similarly connected with the intercooler by a pipe 52. The cylinders and chambers 41, 42, 48 and 49 are preferably formed in axial parallelism in a block or casting 53, supported from the top plate 54 of the unloader casing by means of stanchion rods 55 and having its bottom closed by a plate 56. The pilot valve 48 is shown mounted on a stem 57, which passes through the said plate 56 and is encircled by a compression spring 58 which normally urges this stem and valve upward to the position shown in Fig. 1. The pilot valve 47, as preferably constructed, is hollow with a closed top, and is kept open by a compression spring 59 housed in the interior of the said valve and in a fixed tubular extension 60. The force of this spring may be adjusted by a screw 61, and in like manner the tension of the springs 43, 44 and 58 may be regulated by setting collars 62 at different points on the rods. The rods 45, 46 and 57 pass loosely through the plate 56, so that the downward movement of the pistons 39 and 40 and of the valve 48 is not opposed by the air beneath them. The under side of the pilot valve 47 is in free communication with the atmosphere through a vent 63 in the tubular extension 60. The pilot valve chamber 50, in addition to the inlet in its top from the receiver, is provided in its side with a port 64 communicating with a pipe 65, this port being in such position that it is uncovered by the valve 48 when the latter is in its uppermost position only. The pilot valve chamber 49 is provided in opposite sides and at the same level with ports 66 and 67, which when the pilot valve 47 is in its lowermost position (see in Figs. 1 and 10) register with an annular circumferential valve channel 68. This valve is also provided with a lateral exhaust port 69 formed through its wall and positioned to register with the ports 67 when the said valve is in its uppermost position; and, in order to insure the registry of these ports at such time, means are provided, as indicated at 70, to keep the valve from turning. The valve 48 is also hollow (see Fig. 8), being closed at the bottom and open at the top, and is provided with a lateral port 71 leading from its interior to a circumferential channel 72, which is positioned to register with the port 64 when the valve is in its lowest position. The top of this valve, against which the receiver pressure acts, is of reduced area, and when the valve is in its upper, normal position, the air pressure is kept from acting on the wider part of the valve because of the provision of ground seating surfaces 80 on the valve and its chamber.

The cylinder 41 has two lateral ports 73 and

and 74 at opposite sides, the one located at its top and the other in a lower position to be uncovered by the piston 39 when the latter is forced downward. The cylinder 42 is also provided with two ports 75 and 76, the port 75 being at the top and the port 76 in position to be uncovered by the piston 40 directly after the latter starts on its downward movement. The pipe 65 leading from port 64 of pilot valve chamber 50 is connected on one hand with port 66 of valve chamber 49 through a connection 77, and on the other hand through piping 78 with port 76 of fluid pressure cylinder 42. Port 67 of pilot valve chamber 49 is connected with port 73 of fluid pressure cylinder 41 by a pipe 79. From port 74 of this cylinder fluid may pass through piping 80 having an automatic non-return valve 81 to port 75 at the top of fluid pressure cylinder 72.

The lower portions of the main valve rods 45 and 46 pass through a bottom plate 82 of the unloader casing and carry pistons 83 and 84 which operate in dash-pot cylinders 85 and 86 having adjustable air vents 87 and 88. The function of these dash-pots is to prevent the main valves 35 and 36 being closed with undue force, and their adjustment is not such as to cause the valves to close gradually with a throttling action.

The body of the unloader casing is preferably of duplicate construction at top and bottom, and its closure plates 54 and 82 are interchangeable with respect thereto, so that the body of the casing can be inverted, thus bringing the intercooler connection 29 at either the right or the left-hand side, as may be made desirable by the lay-out of the plant; and for the same purpose the valve seats 37 are removable and reversible with respect to the valve seat openings in the walls 31. To this end the seats 37 and 38 are formed in removable bushings 89 and 90, which comprise ring portions 91 having the seats ground therein and narrow longitudinal portions 92 connecting the rings.

To invert the body of the casing the unloader is first taken apart and then the body is turned upside down about a horizontal axis perpendicular to the plane of Fig. 1. This brings the intercooler connection at the left instead of at the right and the positions of valves 35 and 36 are interchanged. Now, in order that the valve seats may face the valves, it is necessary to invert them in their openings. When the closure plates are replaced, the plate 54 may still occupy the position at the top and the plate 82 be at the bottom because of the duplicate construction of the ends of the body. It is necessary, however, to reverse the closure plates, so that their right-hand ends are at the left and vice-versa, in order to bring the valve rod openings in vertical alinement with the new positions of the valves. It is

also necessary to reverse the block 53 containing the pilot valves.

The valves 35 and 36 are shown as being built up in the same manner and the description of the preferred construction of 70 one will suffice for both. The valve 35 comprises two end rings 93 and 94 ground to co-operate with the seats 37 and united with each other by longitudinal portions 95. Into these ring portions are screwed heads 75 96 and 97 having central apertures closely fitting the rod 45 and when in position abutting against shoulders formed by an enlargement 98 on the rod. Additional tensile strength is afforded the valve by steel 80 screw bolts 99 which engage threaded openings in the heads 96 and 97.

The operation of the particular embodiment of the invention illustrated will now be briefly described.

During the normal operation of the compressor, the condition of the parts is that shown in Fig. 1; that is to say, the main valve 35 is open, the other main valve 36 is closed, their pistons 39 and 40 are both 90 in their upper positions, the pilot valve 48 is in upper position, and the pilot valve 47 is down. If now the receiver pressure rises above the predetermined value, this pressure acting upon the head of the pilot valve 48 95 depresses the latter against the action of spring 58 until the valve bottoms against the plate 56, when the groove 72 registers with the port 64. This air is then free to pass through connections 65 and 77 to ports 100 66 of pilot valve chamber 49. This valve being down, it may flow around through the circumferential channel 68 to the port 67, whence it passes through the pipe 79 to port 73 at the top of cylinder 41. The pressure 105 acting upon the top of piston 39 in this cylinder forces the latter downward against the tension of spring 43 thereby closing the valve 35 upon its seat. When this occurs the piston 39 has uncovered the port 110 74, so that the motive fluid may flow by way of pipes 80 to port 75 at the top of fluid pressure cylinder 42. In this way the piston 40 is forced downward to open the main valve 36, but not until after the main 115 valve 35 is closed. While this condition continues, the intake of the low pressure stage of the compressor is cut off from the atmosphere, so that no more atmospheric air is taken into the compressor, but instead 120 the intake is placed in communication with the intercooler to which the low pressure stage delivers, so that the piston of this stage operates idly, drawing air from and returning it to the intercooler without doing 125 work thereon. The cylinder of the high pressure stage of the compressor is meanwhile taking air from the intercooler, so that the pressure in the latter falls, and when it is reduced to the desired degree or 130

practically to atmospheric pressure, the pilot valve 47 rises, because the intercooler pressure acting through pipe 52 is no longer strong enough to overbalance the spring 59.

5 This upward movement of the pilot valve 47 interrupts the fluid pressure connection between pilot valve chamber 50 and the fluid pressure cylinder 41, and instead brings the exhaust port 69 into registry with port 67, with the result that the space above the piston 39 is placed in communication with the atmosphere, so that the spring 43 promptly reopens the main valve 35. The fluid pressure cylinder 42, however, is not 10 exhausted, the valve 81 closing against any back flow through the pipe 80; and fluid pressure continues to act upon the piston 40 through the port 76 which was uncovered when the said piston moved downward.

15 Therefore, the piston 40 is not allowed to rise and the main valve 36 remains open. Now both the intake and the intercooler are open to the atmosphere, so that the piston of the low pressure stage of the compressor 20 continues to operate idly, circulating atmospheric air through its cylinder. The high pressure stage from now on operates as a single stage compressor, receiving atmospheric air from the intercooler, compressing it and delivering it into the receiver. However, as stated, my invention 25 does not necessarily exclude the provision of suitable means for unloading the high pressure stage as well as the low pressure stage. The circulation of atmospheric air through the low pressure stage during this period together with the action of the usual water-jacket has a decided cooling effect upon this stage, so that for a time after the 30 normal operation is resumed the volumetric efficiency of the compressor is substantially increased. It may now be assumed that the receiver pressure falls below the critical value, thus permitting the pilot valve 48 to rise. This cuts off cylinder 42 from the supply of motive fluid and permits the same to exhaust to the atmosphere through connections 78 and 65 when the lower end of the valve uncovers port 64. This enables 35 spring 44 to raise piston 40 and close the main valve 36. In this way the normal condition is restored and the compressor resumes full load, its intake being open to the atmosphere but cut off from the intercooler.

40 One other condition remains to be considered. This is the contingency that the receiver pressure may fall below the critical value before the action of the piston of the high pressure stage of the compressor has 45 reduced the pressure in the intercooler to that of the atmosphere, or to such low point as will permit the pilot valve 47 to be raised by its spring 59 or the action of atmospheric pressure below said valve. The result of 50 the upward movement of pilot valve 48

under the condition indicated is to cut off both of the cylinders 41 and 42 from fluid pressure and to connect both of them with the atmosphere, so that their pistons may rise under the action of the springs 43 and 44. The exhaust passage from cylinder 42, however, is much more direct and may also be of larger cross-section than that from cylinder 41, and the spring 44 is preferably stronger than the spring 43, so that the main 55 valve 36 is seated before main valve 35 is reopened, thus avoiding loss of such pressure as remains in the intercooler. In this connection it may be noted that the ends of the main valve 36 are of unequal area, the arrangement being such that the pressure left in the intercooler has an increasing effect to close this valve the nearer it approaches its seats. Consequently the closing of the port 76 by the piston 40 when the latter has 60 almost reached its upper position does not check the closing of the main valve 36. The clearance above the piston 40 is so greatly augmented by the interior of the piping 80 that the compression of air by the said piston after closing port 76 is negligible.

The purpose of reducing the area of the pilot valve 48 initially exposed to receiver pressure and of the provision of the seat 80, is to cause this valve to yield only to an 65 excess pressure in the receiver, that is to say a pressure greater than that necessary to continue the downward movement of the valve and to hold it down, after its movement has once been started. This obviates 70 fluttering of the valve. It also results that the valve returns to normal position at a somewhat lower receiver pressure than that which is required to move it from normal 75 position.

Fig. 9 shows a slight modification in respect to the springs which restore the main valves to their normal positions. This arrangement is suitable more particularly for unloaders of large size, for which extension 80 springs are more desirable than compression springs. Two such springs 43^a are shown at opposite sides of the valve rod 45^a, being adjustably connected at their upper ends by means of eye bolts 100 to a cross-piece 101 85 on top of the block 53, their lower ends being secured to a cross-piece 102 bearing against an adjustable collar or nut 103 on the valve rod.

The compressor has been referred to for 90 convenience as an air compressor, but it will be understood that the invention is equally applicable to gas compressors. The term "atmosphere" therefore means merely the source from which the compressor draws the 95 fluid to be compressed, and "atmospheric pressure" means the pressure of the source. The term "receiver pressure" is employed as a convenient one meaning pressure at the 100 delivery side of the compressor, or a

point beyond the stage which operates upon the partly compressed fluid from the intercooler. This term is not intended, therefore, to limit the invention to the employment of a receiver.

5 What I claim as new is:

1. The combination of a multi-stage air or gas compressor having an intercooler, and means controlled by receiver pressure and operative when the same reaches a predetermined value to shut off the intake of the low pressure cylinder from the source and thereupon to place said intake in communication with the intercooler.
- 15 2. The combination of a multi-stage air or gas compressor having an intercooler, means controlled by receiver pressure and operative when the same reaches a predetermined value to shut off the intake of the low pressure cylinder from the source and thereupon to place said intake in communication with the intercooler, and means controlled by the intercooler pressure and operative to connect both the intake and the 25 intercooler with the source when the pressure in the intercooler has been reduced approximately to that of the source by the continued operation of the high pressure cylinder piston.
- 30 3. The combination of a multi-stage air or gas compressor having an intercooler, means controlled by receiver pressure and operative when the same reaches a predetermined value to shut off the intake of the low pressure cylinder from the source and thereupon to place said intake in communication with the intercooler, and means connected with the intercooler and operative 35 upon a predetermined lowering of pressure 40 therein to re-open the intake to the source, the communication between the intake and intercooler remaining open.
4. The combination of a multi-stage air or gas compressor having an intercooler, 45 means controlled by receiver pressure and operative when the same reaches a predetermined value to shut off the intake of the low pressure cylinder from the source and thereupon to place said intake in communication with the intercooler, means connected 50 with the intercooler and operative upon a predetermined lowering of pressure therein to re-open the intake to the source, the communication between the intake and intercooler remaining open, and means whereby 55 the said communication is closed when the receiver pressure falls below a critical value.
5. The combination of a multi-stage air or gas compressor having an intercooler, 60 means controlled by receiver pressure and operative when the same reaches a predetermined value to shut off the intake of the low pressure cylinder from the source and thereupon to place said intake in communication with the intercooler, means connected 65

with the intercooler and operative upon a predetermined lowering of pressure therein to re-open the intake to the source, the communication between the intake and intercooler remaining open, and means whereby the communication between the intake and the intercooler is closed and that between the intake and source re-opened, in event of the receiver pressure falling to a critical value before the supply of compressed fluid 70 trapped in the intercooler has been exhausted.

6. An unloader connected with the intake of a stage of a multi-stage air or gas compressor and comprising two valves, the first of said valves constructed to open and close communication between said intake and the source and the second to open and close communication between the intake and the intercooler to which said stage delivers, and means controlled by receiver pressure and operative when the same reaches a predetermined value to close the first valve and then 80 to open the second valve.

7. An unloader connected with the intake of a stage of a multi-stage air or gas compressor and comprising two valves, the first of said valves constructed and arranged to open and close communication between said intake and the source, the second to open 95 and close communication between the intake and the intercooler to which said stage delivers, means controlled by receiver pressure and operative when the same rises to a predetermined value to close the first valve, and 100 means dependent upon the closing of the first valve whereby the second valve is opened.

8. An unloader connected with the intake of a stage of a multi-stage air or gas compressor and comprising two valves, the first of said valves constructed and arranged to open and close communication between said intake and the source, the second to open and close communication between the intake and the intercooler to which said stage delivers, pistons connected with said valves, and fluid pressure connections whereby said pistons are operated when the receiver pressure rises to a predetermined value to close 105 the first valve, thereby shutting off the intake from the source, and to open the second valve, thereby connecting the intake with the said intercooler.

9. An unloader connected with the intake of a stage of a multi-stage air or gas compressor and comprising two valves, the first of said valves constructed and arranged to open and close communication between said intake and the source, the second to open and close communication between the intake and the intercooler to which said stage delivers, pistons connected with said valves, fluid pressure connections whereby said pistons 110 are operated when the receiver pressure rises 115

- to a predetermined value to close the first valve, thereby shutting off the intake from the source, and to open the second valve, thereby connecting the intake with the said intercooler, and further connections whereby the first valve is again opened, the second valve remaining open, when the compressed fluid in the intercooler has been sufficiently exhausted.
10. An unloader connected with the intake of a stage of a multi-stage air or gas compressor and comprising two valves, the first of said valves constructed and arranged to open and close communication between the intake and the source, the second to open and close communication between the intake and the intercooler to which said stage delivers, pistons connected with said valves, fluid pressure connections whereby said pistons are operated when the receiver pressure rises to a predetermined value to close the first valve, thereby shutting off the intake from the source, and to open the second valve, thereby connecting the intake with the intercooler, whereby at this time the next higher stage of the compressor exhausts the compressed fluid trapped in the intercooler and the lower stage operates idly, taking fluid from and returning it to the intercooler, further connections whereby the first valve is again opened, the second valve remaining open, when the compressed fluid in the intercooler has been sufficiently exhausted, so that thereafter the higher stage of the compressor receives fluid at the pressure of the source while the lower stage is cooled by the circulation of fluid therethrough, the first mentioned connections causing the second valve again to close, the first valve remaining open, when the receiver pressure falls below a critical value, thereby restoring the normal condition.
11. An unloader connected with the intake of a multi-stage air or gas compressor and comprising two valves, the first of said valves constructed and arranged to open and close communication between the intake and the source, the second to open and close communication between the intake and the intercooler to which said stage delivers, fluid pressure means for operating said valves, and means for controlling the operation of the same, including connections with a source of pressure at the delivery side of the compressor whereby the first valve is closed and the second thereupon opened when such pressure rises to a predetermined value, connections with the intercooler of the compressor whereby the first valve is opened, the second remaining open, when compressed fluid trapped in the intercooler has been sufficiently exhausted, means whereby the second valve is again closed, the first remaining open, when the receiver pressure falls below a critical value, and means whereby the second valve is closed and the first thereupon opened in event of the pressure at the delivery side falling to the critical value before the compressed fluid trapped in the intercooler has been exhausted.
12. An unloader connected with the intake of a stage of a multi-stage compressor and comprising two main valves, the first adapted to open and close communication between said intake and the source, and the second to open and close communication between the intake and the intercooler to which said stage delivers, fluid pressure cylinders and pistons for the operation of said valves, and two pilot valves controlling the operation of said pistons, one of said pilot valves being operated by receiver pressure and the other by intercooler pressure.
13. An unloader connected with the intake of a stage of a multi-stage compressor and comprising two main valves, the first adapted to open and close communication between said intake and the source, and the second to open and close communication between the intake and the intercooler to which said stage delivers, fluid pressure cylinders and pistons for the operation of said valves, a pilot valve and a line whereby the same is controlled by receiver pressure to admit fluid to the fluid pressure cylinder of the first main valve, a connection between the said cylinder and the fluid pressure cylinder of the second main valve, and a second pilot valve and a line whereby the same is controlled by intercooler pressure, the said second pilot valve being interposed in the passage between the first pilot valve and the fluid pressure cylinder of the first main valve.
14. An unloader connected with the intake of a stage of a multi-stage compressor and comprising two main valves, the first adapted to open and close communication between said intake and the source, and the second to open and close communication between the intake and the intercooler to which said stage delivers, fluid pressure cylinders and pistons for the operation of said valves, a pilot valve and a line whereby the same is controlled by receiver pressure to admit fluid to the fluid pressure cylinder of the first main valve, a connection between the said cylinder and the fluid pressure cylinder of the second main valve, and a second pilot valve and a line whereby the same is controlled by intercooler pressure, the said second pilot valve being interposed in the passage between the first pilot valve and the fluid pressure cylinder of the first main valve and having means for connecting said cylinder with an exhaust, there being a check-valve in the connection between the two fluid pressure cylinders containing said pistons to prevent exhaustion of the second cylinder by the first.

15. An unloader connected with the intake of a stage of a multi-stage compressor and comprising two main valves, the first adapted to open and close communication between said intake and the source, and the second to open and close communication between the intake and the intercooler to which said stage delivers, fluid pressure cylinders and pistons for the operation of said valves, said fluid pressure cylinders being connected in series by a passage having a check-valve therein, a pilot valve controlled by receiver pressure for controlling the admission of fluid pressure to the fluid pressure cylinder of the first main valve, a second pilot valve controlled by intercooler pressure, the said second pilot valve being interposed in the connection between the first pilot valve and the fluid pressure cylinder of the first main valve, and being adapted upon decrease in intercooler pressure to interrupt said connection and to exhaust the said fluid pressure cylinder, and a further connection between the first pilot valve and the fluid pressure cylinder of the second main valve whereby to hold the piston in this cylinder in actuated position after the return of the other piston and to exhaust the said cylinder when the receiver pressure falls below the critical value.

16. An unloader connected with the intake of a stage of a multi-stage compressor and comprising two main valves, the first adapted to open and close communication between said intake and the source, and the second to open and close communication between the intake and the intercooler to which said stage delivers, fluid pressure cylinders and pistons for the operation of said valves, said fluid pressure cylinders being connected in series, a pilot valve in a valve chamber connected with a receiver line, the said valve having a hollow interior open to receiver pressure and a transverse port communicating with its interior, a passage with which said transverse port communicates when the said valve is actuated, said passage leading to the fluid pressure cylinder of the first main valve, a second pilot valve in a valve chamber connected with an intercooler line, said second pilot valve having a circumferential channel forming part of the last-mentioned passage and having also a hollow interior and a transverse exhaust port adapted to exhaust the fluid pressure cylinder of the first main valve when the intercooler pressure has been reduced to a predetermined value.

17. An unloader designed for connection with the intake of a stage of a multi-stage air or gas compressor, comprising a casing having walls therein forming a chamber open to the source, a chamber open to the said intake and a chamber having means of connection with the intercooler to which

said stage delivers, a valve constructed and arranged to open and close communication between the source and intake chambers, a second valve constructed and arranged to open and close communication between the intake and intercooler chambers, and means operating said valves, substantially as described.

18. An unloader designed for connection with the intake of a stage of a multi-stage air or gas compressor comprising a plurality of main valves adapted to open and close communication between said intake and the source, and between the intake and the intercooler to which said stage delivers, fluid pressure cylinders and pistons for the operation of said valves, and a plurality of pilot valves responsive to pressures in different parts of the compressor system and controlling the flow of motive fluid in respect to said cylinders.

19. The combination with a multi-stage air or gas compressor, of an unloader connected with the intake thereof and comprising main valves adapted to open and close communication between the intake and the source and between the intake and the intercooler, respectively, motors for operating said valves, and pilot valves exposed to receiver and intercooler pressures, respectively, and controlling the operation of said motors, substantially as described.

20. An unloader connected with the intake of a stage of a multi-stage compressor and comprising two main valves adapted to open and close communication between said intake and the source and between the intake and the intercooler to which said stage delivers, respectively, fluid pressure cylinders, pistons and passages for operating said valves, a pilot valve responsive to receiver pressure controlling passages of both cylinders, and another pilot valve controlling passages of one of the cylinders and responsive to intercooler pressure.

21. An unloader for connection with the intake of a multi-stage air compressor, the same comprising a casing formed at opposite sides with an inlet from the source and an outlet to the intake, and being further provided with an intercooler connection at right angles to said inlet and outlet, walls in said casing dividing the same into three chambers open, respectively, to said inlet, outlet and intercooler connection, and two double-seat valves in said casing co-operating with seats in said walls to control communication between the chambers.

22. An unloader for connection with the intake of a multi-stage air compressor, the same comprising a casing having an inlet connection, an outlet connection to the intake of the compressor, and an intercooler connection, and being divided internally into three chambers open to the three connec-

tions, and two valves in said casing controlling communication between the three chambers.

23. An unloader for multi-stage compressors, comprising a body having interchangeable top and bottom heads, three external connections and walls dividing its interior into three corresponding chambers communicating with each other by openings
10 for double seat valves, valve seat bushings

reversibly mounted in said openings, and valves coöperative with said seats.

24. An unloader for multi-stage compressors, comprising a reversible body having internal walls formed with openings for a 15 double-seat valve, a valve seat bushing reversibly mounted in said openings, and a valve coöperating with said bushing.
